UNITED STATES PATENT OFFICE.

OSCAR L. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

SCAVENGER FOR SPINNING-MACHINES.

1,269,847.

Specification of Letters Patent. Patented June 18, 1918.

Application filed August 31, 1911. Serial No. 646,981.

To all whom it may concern:

Be it known that I, OSCAR L. OWEN, a citizen of the United States, residing in Whitinsville, Worcester county, State of Massachusetts, have invented a new and useful Improvement in Scavengers for Spinning-Machines, set forth in the following specification.

The object of the invention is to make use of a traveling conveyer belt for scavenging spinning machines, having the least complication of structure and the fewest number of parts in its organization. The invention includes to this end various important features of construction, arrangement and operation whereby a traveling scavenger belt can be applied to existing types of spinning machines with slight alteration, rendering them more efficient by the automatic removal of the broken ends of roving. The invention is of special utility in connection with spinning machines used on short fiber or so-called waste cotton, where breakages in the roving occur with frequency.

In the accompanying two sheets of drawings forming part of this specification,

Figure 1 is an end elevation of a spinning machine equipped with the new scavenger device, parts of the end frame upright thereof being broken out to show the interior arrangement;

Fig. 2 is a slightly enlarged transverse section of the machine of Fig. 1 taken in a plane at one end of the scavenger belt;

Fig. 3 is a side elevation of the same machine on a smaller scale than Fig. 1 with parts broken away;

Fig. 4 is a perspective detail of the overhanging end of the scavenger belt; and

Fig. 5 is a detail of the belt clearer brush.

The spinning machine taken for illustration has a frame composed of three uprights marked 1, 2 and 3 respectively, carrying the longitudinal bolster rails 4 and the roller beams 5, the latter bearing the creel superstructure 6. The roller beams 5 on both sides of the frame are formed of angle iron, as shown in Figs. 1 and 2, with a vertical front flange and a horizontal top flange upon which the roll stands 7 are mounted, the standards of these stands being of forwardly inclined or goose-neck

formation so that their journal-heads overhang the vertical front flange in order to support the drawing or delivery rolls 8 with the last pair of rolls in the series disposed directly over the space in front of the roller beam. In this position broken ends of roving issuing from the delivery rolls will hang or fall directly down into the space in front of the roller beam. The front flange of the roller beam is provided with a series of forwardly projecting studs 9 spaced at intervals along its length, and at the forward ends of these studs there is mounted a rail 10 upon which the row of thread-guides 11 is supported. In the present case the thread-guides are mounted in finger-heads 12 which are pivoted to an intermediate support 13, the latter being hinged to the rail 10 and normally supported in the position indicated in the drawings. The support 13 has a handle 13^a appearing in Figs. 3 and 4. The support 13 or supports for the thread-guides, as thus mounted, are separated from the roller beam by a horizontally extending space of about three or four inches in width, which space is centralized with respect to the position of the delivery rolls above referred to and extends horizontally adjacent the upper front part of the roller beam for the full length of the spinning machine, that is to say, from the first spindle adjacent the frame upright 1 to and through the upright 3 at the opposite end of the machine.

Power is applied to the machine at the drive pulley 14 mounted adjacent the end frame upright 1 on a longitudinal shaft 15 which carries and drives the spindle band drum 16 by which the spindles 17 are rotated in their bolster rails 4 on both sides of the machine. The upright 1 is hollow and forms a housing for a gearing train marked 18 through which the power shaft by a connection, not shown, drives the several delivery rolls and also the supply drum 19 in the creel. The shaft 20 of one of the gears of this train is extended through the wall of the housing in a boss 21, inwardly to a point adjacent the first spindle in the roll where it is provided with a worm 22 meshing with a worm-wheel 23 of a cross-shaft 24. This cross-shaft is journaled horizontally in two brackets 25, each of which is bolted to the

inner side of the vertical front flanges of the roller beams 5, and extends at both ends somewhat beyond the brackets and beams where it carries the drive pulleys 26, the latter being thus located in the space in front of the roller beam above referred to and at one end of the latter and adjacent to the first spindle in the row. The pulley has a radius about equal to the depth of the roller beam flange and is thus adapted to support the scavenger belt 27 in a position slightly below the level of the row of thread-guides but above the supporting studs 9 by which the latter are carried. The bracket 25 also carries the support for a belt-guide pulley 28 shown in Fig. 3, which pulley is mounted with its axis on substantially the same level as that of the cross-shaft 24.

The scavenger belt 27 is of about the width of the space between the front of the roller beam and the rear face of the thread-guide supporting rail, and extends in a horizontal plane through such space and below the top thereof to a point somewhat beyond the end of the roller beam and the adjacent end frame upright 3, the latter being recessed as indicated at 3^a in Fig. 4 to permit the belt to pass through and project beyond the end of the machine frame as shown in Fig. 3. At this point the belt is carried on a suitable guide such as the idle pulley 29, passing around the same and back to the drive pulley over a clearer brush 30, a take-up pulley 31 and the guide pulley 28 above referred to. The take-up 31 is adjustably mounted on the intermediate frame upright and is adapted to vary the tension of the belt as desired. The clearer brush 30 which is separately shown in Fig. 5 is formed with bristles at two elevations, the shorter bristles being in the middle to engage the face of the belt, and the longer bristles being at the sides to clear the edges of adhering fibers and the material of which the belt is made being of such degree of smoothness as to permit the ready dislodgment of the yarn by this means. The brush stock 32 in which the bristles are mounted is adjustably bolted to the end frame upright 3 immediately beneath the lower edge of the belt recess 3^a, the adjustment being for the purpose of taking up wear. The guide pulley 29 is mounted on a sleeve 33, adjustably set-screwed upon a stud 34 secured to the outer side of the upright 3 parallel with the roller beam, so that the pulley can be moved horizontally to accommodate the length of the belt. The position of the pulley projecting beyond the end of the machine frame provides for the placing of a box 35 directly beneath the end of the operating stretch of the scavenger belt to catch the droppings therefrom. Such box can be mounted on a shelf or upon the floor, or it can be attached to the end frame as shown in the drawings. The rail 10 can,

if desired, be provided with an extension 10^a following the contour of the belt around the guide pulley 29 as indicated in Figs. 3 and 4, for the purpose of continuing the guiding effect of the rail upon the belt beyond the end of the frame. Such extension is desirable for keeping the cotton on the belt from falling off at one side, as well as to guard the belt from accidental contact.

In the operation of the machine the roving passes from the creel through the rolls 8, thence through the thread-guides and thence to the travelers on the ring-rail 36 in the usual manner. In the case of a break in the roving the broken end will fall downwardly as indicated in Fig. 2 and upon the top of the upper stretch of the conveyer belt 27 which is driven at a speed not exceeding the surface speed of the drawing rolls, being carried thereon and deposited in the box 35 at the end of the machine without conflict with the other unbroken rovings. The location of the upper stretch of the belt between the roller beam and the longitudinal supporting member of the thread-guides keeps the roving from falling off of the edge of the belt, and at the same time forms a shelter for the spindle bands and other lower parts of the mechanism of the machine, protecting them against accumulations of fly. The mounting of the scavenger belt and its relation to the other parts is such that it can be removed from the machine without unlacing, by removing the tension thereon and slipping it laterally over the thread-guide supporting rail.

I claim:

1. In a spinning machine, the combination of end frame uprights connected by a roller-beam bearing delivery rolls, a row of thread-guides supported in advance of the roller-beam and separated therefrom by a space extending the length of the machine and defined by lateral walls, a pulley within said space near one end, a second pulley supported in projecting relation at the far end of the space, and a scavenger belt on said pulleys having a horizontal upper stretch running between said walls and adapted to receive broken rovings from the delivery rolls directly by gravity and to deliver the same by gravity at its projecting end into a suitable receptacle placed outside of the machine.

2. In a spinning machine, the combination of end frame uprights connected by a roller-beam bearing delivery rolls, a row of thread-guides supported in advance of the roller-beam and separated therefrom by a space extending the length of the machine and defined by lateral walls, a pulley within said space near one end frame, the remote end frame having a recess in line with said space, a second pulley supported in projecting relation at said recess, and a scav-

enger belt on said pulleys having a horizontal upper stretch running between said walls and adapted to receive broken rovings from the delivery rolls directly by gravity and to 5 deliver the same by gravity at its projecting end into a suitable receptacle placed outside of the machine.

3. In a spinning machine, a roller-beam bearing delivery rolls, and a row of thread-guides spaced in front of the roller-beam, in combination with a scavenger belt in said space having a horizontal upper stretch adjacent the roller beam, and gearing for driving said belt disposed behind and below 15 the level of the roller-beam.

4. A spinning machine having at opposite sides roller-beams bearing delivery rolls, and a row of thread-guides spaced in front of each roller-beam, in combination with a 20 scavenger belt operative in each of said spaces and having a horizontal upper stretch, and gearing for driving said belts disposed behind and below the level of the roller-beams and including a cross-shaft bearing belt-driving pulleys at its opposite 25 ends.

5. In a spinning machine, the combination with a supporting frame comprising end frame uprights connected by a roller beam, a series of roll-stands carrying delivery rolls, and a series of thread-guides in front of the same, said series of thread guides being separated from the roller beam by a longitudinal space defined by upright 30 walls, and a scavenger belt having its upper stretch disposed in a substantially horizontal plane and guided between said walls, the belt being perpendicular at its edges to 35 said walls and extended at its delivery end beyond one of the end frame uprights to allow 40 rovings to fall off beyond the frame by gravity.

6. In a spinning machine, the combination with a roller-beam, supports projecting 45 forward therefrom, and a thread-guide supporting rail spaced horizontally in front of said roller-beam on said supports, of a scavenger belt, pulleys for supporting and driving the same with its upper and lower 50 stretches above and below said supports respectively and its upper stretch below the top of such space, and belt take-up means, whereby by removing the tension on the belt 55 the same can be removed from the machine by slipping it over the thread-guide rail.

7. In a spinning machine, the combination with a roller-beam, and a row of thread-guides supported by and spaced horizontally in front of the same, of a scavenger 60 belt, pulleys for supporting and driving the same in such space, and take-up devices operative to press the lower stretch of the belt upwardly and away from subjacent parts.

8. In a spinning machine, a roller-beam, 65 a thread-guide supporting rail spaced hori-

zontally in front of said roller-beam, and supporting end uprights one of which is recessed at the end of such space, in combination with a scavenger belt, means for supporting and driving the same in such space 70 with its terminal portion projecting through said recess, and an extension from the adjacent end of said thread-guide supporting rail disposed in front of and guarding the outwardly projecting portion of the belt. 75

9. In a spinning machine, a roller-beam, and a thread-guide supporting rail spaced horizontally from each other, in combination with a scavenger belt disposed between said beam and rail with its upper stretch 30 horizontal and its terminal portion projecting beyond the adjacent end of the roller-beam, and means carried by said thread-guide supporting rail for guarding the projecting portion of said belt. 85

10. In a spinning machine, the combination with a roller-beam with its roll stands, and a thread-guide supporting rail spaced horizontally in front of the roller-beam, of a scavenger belt located in and approximately the width of the space between the roller-beam and thread-guide supporting rail, its upper stretch being horizontal and disposed below the tops of said beam and rail and traveling at its edges in guided relation to the faces thereof, which serve as guards to retain the material carried by the belt, and a plurality of studs extending between said roller-beam and thread-guide supporting rail and beneath the upper 95 stretch of said belt, thereby both supporting the thread-guide supporting rail and sustaining the upper stretch of the belt. 100

11. In a spinning machine the combination with the roller-beam, a bracket secured 105 to the inner side thereof, and a shaft journaled in the bracket, of a pulley on the shaft at the opposite side of the roller-beam and a scavenger belt driven by the pulley.

12. In a spinning machine, the combination of the roller beam having a vertical front flange or face and a thread-guide-supporting rail having an opposing face spaced therefrom and a scavenger belt having its upper stretch mounted to travel 110 through the space between said beam and rail, said faces being closely adjacent and extending above the edges of the upper course of the belt. 115

13. A spinning machine having a roller beam and a thread guide supporting rail together forming a trackway for a conveyer belt and drawing rolls on the roller beam overhanging said trackway, in combination with two pulleys near the ends of the trackway, and a conveyer belt stretched on said pulleys and having its upper stretch laterally guided by the aforesaid beam and rail on either side thereof. 125

14. A spinning machine having end frame 130

uprights, a roller-beam supported thereon, a thread-guide support in spaced relation to said roller-beam, delivery rolls supported on the roller beam, and driving gears for said 5 rolls housed within one of the end uprights, in combination with a scavenger belt mounted parallel to the roller beam and between the same and the thread-guide support, a driving cross-shaft therefor extending beneath the roller beam, and a shaft connecting said cross-shaft with one of the gears in the said end frame upright.

15. A spinning machine having a roller beam with a vertical front flange, a rail supported opposite said flange, a horizontal cross-shaft projecting forwardly beneath said front flange and a pulley carried on the cross-shaft to rotate adjacent and in front of the front flange, in combination with a 20 belt occupying the space between said flange and rail and driven by the pulley and a guide supporting the belt at the end of the machine.

16. In a spinning machine, a roller beam 25 provided with forwardly projecting studs and a thread-guide supporting rail supported on the studs, in combination with a conveyer belt mounted in the space between the beam and rail and having its upper and 30 lower stretches respectively above and below the said supports for the rail.

17. In a spinning machine, a roller beam, supports projecting therefrom, a thread-guide supporting rail carried on the supports and a scavenger belt circling said supports, in combination with a drive pulley 25 for said belt near one end of the machine and a guide pulley therefor projecting be-

yond the end of the roller beam at the other end of the machine.

18. In a spinning machine, the combination of roll-stands, delivery rolls carried thereby and supported above and in front of the bases of said stands, a row of thread guides spaced in front of said rolls and a 45 flat smooth-surfaced conveyer belt having an upper stretch disposed substantially in a horizontal plane and extending substantially horizontally lengthwise of the machine in the rear of said thread guides and 50 directly beneath said delivery rolls to receive broken rovings directly by gravity from said rolls and means for driving said belt at a speed not exceeding the speed of delivery of material from said rolls.

19. In a spinning machine, the combination of delivery rolls, a row of thread guides spaced in front of said rolls and a conveyer belt having an upper stretch disposed substantially in a horizontal plane 55 and movable substantially horizontally lengthwise of the machine in the rear of said thread guides and directly beneath said delivery rolls to receive broken rovings directly by gravity from said rolls, and means for driving said belt at a speed not exceeding the speed of delivery of material from 60 said rolls.

In testimony whereof, I have signed this specification in the presence of two witnesses.

OSCAR L. OWEN.
